(57) **CLAIM**

The ornamental design for a weight activated restraining pillow, as shown.

DESCRIPTION

FIG. 1 is a perspective view of a weight activated restraining pillow;

FIG. 2 is a top plan view of a weight activated restraining pillow;

FIG. 3 is a bottom plan view of a weight activated restraining pillow;

FIG. 4 is a side view of a weight activated restraining pillow; and,

FIG. 5 is an end view of a weight activated restraining pillow. The broken lines in the drawing represent stitching.
